PISTON GRINDING APPARATUS

Clarence J. Green, Worcester, Mass., assignor to
Norton Company, Worcester, Mass., a corpora-
tion of Massachusetts

Application September 16, 1938, Serial No. 230,261

9 Claims. (Cl. 51—101)

The invention relates to grinding machines, and more particularly to a grinding machine for grinding a work piece of non-circular cross section.

5 One object of the invention is to provide a simple and thoroughly practical grinding machine for grinding a work piece to a non-circular shape such, for example, as a cam, an oval shape on an automotive piston or the like. Another object 10 of the invention is to provide a grinding machine for grinding a work piece of non-circular cross section in which the work piece is rocked toward and from the grinding wheel by means of a rotatable cam. A further object of the invention is to provide a grinding apparatus of such a type that the extent of the motion transmitted by the cam may be adjusted. Other objects 15 will be in part obvious or in part pointed out hereinafter.

20 The invention accordingly consists in the features of construction, combinations of elements, and arrangements of parts, as will be exemplified in the structure to be hereinafter described, and the scope of the application of which will be indicated in the following claims.

In the accompanying drawings in which is shown one of various possible embodiments of the mechanical features of this invention,

Fig. 1 is a front elevation of a grinding machine embodying the improved grinding attachment;

Fig. 2 is a fragmentary front elevation, on an enlarged scale, of the improved grinding attachment, showing the driving mechanism;

35 Fig. 3 is a fragmentary sectional view taken approximately on the line 3—3 of Fig. 2;

Fig. 4 is an end elevation of a modified construction;

Fig. 5 is a modification of the arrangement 40 shown in Fig. 3; and

Fig. 6 is a fragmentary sectional view, on an enlarged scale, through the pivot stud.

A cylindrical grinding machine has been illustrated in the drawings comprising a base 10 which supports a longitudinally reciprocable table 11 on the usual flat and V-ways (not shown). The longitudinally reciprocable table 11 is provided with a motor driven headstock 16 having a rotatable spindle 17 which is driven by an electric motor 18. The headstock serves as a driving means for an improved grinding attachment to be hereinafter described.

A rotatable grinding wheel 20 is supported on a rotatable wheel spindle 21 which is in turn supported on a wheel slide 22. The wheel slide 22

is arranged to slide transversely on the base 10 on a pair of spaced slideways (not shown). The wheel spindle 21 and grinding wheel 19 may be rotated by means of an electric motor 19 mounted on top of the wheel slide 22. The wheel slide 22 is arranged to be moved transversely relative to the base 10 by means of a suitable wheel feeding mechanism. The wheel feeding mechanism may be of any well known type such as, for example, that shown in the prior United States patent to C. H. Norton No. 762,838 dated June 14, 1904. This mechanism has not been shown in detail in the present case, since it is not considered to be part of the present invention. For details of disclosure, reference may be had to the above mentioned patent. A manually operable rotatable feed wheel 25 is mounted on the front of the machine base 10 and is operatively connected to rotate a feed screw (not shown) to cause the grinding wheel 20 and wheel slide 22 to be moved transversely toward or from the work supporting table 11, depending upon the direction of rotation of the feed wheel 25. In the construction illustrated in the drawings, the feed wheel 25 may be actuated manually or automatically, as desired. A mechanically actuated feed pawl 26, such as that shown in the prior patent above referred to, is reciprocated automatically to advance the wheel at the ends of the reciprocatory stroke of the work table.

In the construction illustrated in the drawings, the work supporting table 11 is arranged to be reciprocated longitudinally relative to the base 10 and the grinding wheel 20 to traverse the work piece past the operative face of the grinding wheel 20. The table 11 is provided with a depending rack bar 30 by which the table may be traversed by a manual or power traverse mechanism, such as that shown in the prior patent above referred to. Reference may be had to the above mentioned expired patent for details of disclosure not contained herein. A gear 31 meshes with the rack 30 and is mounted on a rotatable shaft 32 which may be rotated manually by means of a gear 33 mounted on the outer end of the shaft 32. A manually operable traverse wheel 35 is mounted on the outer end of a shaft 34 and is connected by a gear 35 to rotate the gear 33, the gear 31, and the rack bar 30 so that the table 11 may be traversed longitudinally when desired.

The table 11 may be reciprocated longitudinally by a power operated mechanism, such as that shown in the prior patent above referred to. This mechanism may comprise a rotatable power

driven shaft 40 which is driven by means of a multiple speed drive contained within a casing 41, the details of which have not been shown in the present case since they are not considered 5 to be part of the present invention. For details of this mechanism, reference may be had to the above mentioned prior patent. The rotatable shaft 40 is connected through a reversing clutch (not shown) which is actuated by means of a 10 reversing lever 43. The reversing lever 43 is actuated by reversing dogs 44 and 45 which are adjustably mounted in a T-slot 46 formed in the front edge of the table 11.

In the production of automobile pistons, it is 15 frequently desirable to grind either a portion of the piston or the entire outer surface of the piston to an oval or elliptical form. It is desirable to provide a grinding apparatus which is arranged to oscillate the work supporting spindle toward 20 and from the grinding element so as to produce the desired shape, either oval, elliptical or otherwise, on the periphery of the piston or work piece being ground. For a production grinding machine, such an apparatus may be built into the 25 machine as a permanent part of the machine or may be made in the form of an attachment, as illustrated, which may be readily applied to a standard cylindrical grinding machine.

The improved piston grinding attachment may 30 comprise a frame 50 which is provided with a dovetailed surface 51 which mates with correspondingly shaped surfaces on the table 11. A clamping block 52 which is held in place by means of a clamping screw 53 serves to clamp the frame 35 50 rigidly in position on the work table 11. The frame 50 serves as a support for a rock bar 55 which is provided with upwardly extending bosses 56 and 57 each of which serve as supports for bearings 58 and 59, respectively. Trunnion shafts 40 and 61 are rigidly fastened to the ends of the rock bar 55 respectively and serve as a pivotal support for the rock bar 55. The rock bar 55 is provided with two upwardly extending bearing members 65 and 66 which rotatably support 45 a work supporting spindle 67. A piston supporting head 68 is mounted on the right-hand end of the spindle 67 (Fig. 2) and serves as a support for the hollow end of a piston 69 to be ground. The rock bar 55 also supports a footstock 70 having a footstock center 71 which is 50 arranged to engage and support the other end of the piston 69.

A suitable driving mechanism is provided for 55 rotating the work supporting spindle 67 so that the rotative power of the headstock spindle 17 may be transmitted to rotate the work supporting spindle 67. The headstock spindle 17 supports a sprocket 75 on its outer end which is connected by a link chain 76 with a sprocket 77 which is formed as an integral part of a sleeve 78. The sleeve 78 is rotatably supported on the trunnion shaft 60. The sleeve 78 has formed integrally therewith a sprocket 79 which is connected by a link chain 80 with a sprocket 81 which is mounted on the outer end of the work supporting spindle 67. By mounting the driving sleeve and the integral sprockets 77 and 79 on the trunnion shaft 60, the drive between the headstock spindle 17 and the work supporting spindle 67 may be readily accomplished. When the headstock motor 18 is started to rotate the headstock spindle 17, a rotary motion is transmitted through the sprocket 75, the link chain 76, the sprocket 77, the sleeve 78, the sprocket 79, the link chain 70 80, the sprockets 81, to rotate the work support-

ing spindle 67 and thereby rotate the piston 69 to be ground.

In order to grind a surface on a work piece of non-circular cross section, such as a cam or an oval or elliptical surface on an automotive piston, it is necessary to provide a suitable mechanism for rocking the bar 55 in timed relationship with the work rotation so as to produce the desired and predetermined contour on the work piece being ground. In the preferred construction, 5 a master cam 85 is formed integral with or fixedly mounted on the sleeve 78. The master cam 85 and the sleeve 78 are both rotatably supported on the trunnion shaft 60. In order to transmit the motion of the master cam 85 to 10 oscillate the rock bar 55, a master cam roller 86 is rotatably supported on a stud 87 which is in turn supported on the lower end of a pivotally mounted lever 88. The lever 88 is pivotally supported on a pivot stud 89 which is secured to a 15 bracket 90. The bracket 90 is in turn adjustably secured to the attachment frame 50 by means of a clamping screw 91 which passes through an elongated slot 92 in the bracket 90 and is screw threaded into the frame 50.

The upper end of the lever 88 is connected by 20 a stud 93 with an arm 94 the other end of which is provided with a bearing surface within which the spindle 67 rotates. It will be readily apparent from this construction that when the headstock spindle 17 is rotated, the power transmitted to the driving mechanism above described rotates the work supporting spindle 67 and the work piece 69 and at the same time rotates the master cam 85 in synchronism with the rotation of the piston 69 to oscillate the work axis 25 towards and from the grinding wheel during the grinding operation.

In order to facilitate adjustment of the mechanism so that the extent of oval or shape may be 30 varied slightly from that of the master cam 85, an adjustment is provided in the connection between the master cam and the spindle 67. As illustrated in the drawings, the lever 88 is provided with an elongated slot 95 by means of which the 35 fulcrum point of the lever 88 may be adjusted as desired. It is desirable to maintain the axis of the stud 87 supporting the follower roller 86 in the same horizontal plane with the axis of rotation of the master cam 85 and the trunnion shaft 60 during any adjustment of the lever arms. Consequently, if it is desired to change the adjustment of the mechanism, the bracket 90 is 40 adjusted vertically up or down, and the fulcrum stud 89 is adjusted correspondingly so as to vary 45 the lever arm between the stud 87 and the fulcrum stud 89 and also between the fulcrum stud 89 and the stud 93. If the fulcrum stud 89 is positioned midway between the stud 87 supporting 50 the follower roller 86 and the stud 93, then 55 the piston 69 being ground will be rocked by an amount as governed by the rise and fall of the master cam 85.

As illustrated, the master cam has been shown 60 as of a non-circular contour for producing a non-circular contour on the piston 69 being ground. If it is desired to vary the contour of the work piece slightly from that of the master, then the bracket 90 and the fulcrum stud 89 may be adjusted vertically to change the lever arm relationship of the lever 88 so as to increase or decrease the rocking movement of the rock bar 55 for each rise and fall of the cam and thus 65 vary the shape produced upon the piston 69.

For grinding certain types of work, such as a 70 75

non-circular work piece having a plurality of equally spaced, identically shaped lobes projecting therefrom, it may be desirable to utilize a single lobe master cam, such as for example that shown in Fig. 5, to transmit a rocking motion to the rock bar 55 so that each of the projecting lobes on the work piece being ground is formed by the same projection or lobe on the master cam. If there are two identically shaped lobes on the shaft or work piece being ground, then the sprocket and chain driving connection between the sleeve 78 and the spindle 67 will be a two to one reduction, so that the master cam 85a will rotate twice while the spindle 67 is rotating once. A master cam having a single lobe is much less expensive to manufacture than one having, for example, two, three or more lobes. The shape of the single accurately formed lobe may accurately reproduce a plurality of identical lobes on the work piece merely by utilizing the proper gearing between the master cam and the product cam or work piece. It may be desirable when grinding certain types of work to locate the master cam so that it rotates about an axis which is not concentric with the axis of the trunnion shaft 60. Such an arrangement of parts has been illustrated in the modification shown in Fig. 4. A master camshaft 100 is supported in an upwardly extending bracket 101 formed integral with the frame 50. The master camshaft 100 supports a master cam 102 which is engaged by a follower roller 103. The follower roller 103 is supported by a stud 104 at the lower end of a lever 105. The lever 105 is pivotally supported by an adjustable fulcrum stud 106 which is fixed to a bracket 107. The bracket 107 is adjustably mounted on an upwardly extending portion 108 of the frame 50 by means of a clamping screw 109. The upper end of the lever 105 is connected by a stud 110 with one end of a link 111 the other end of which is connected by a stud 112 with a short connecting rod 113 the other end of which surrounds the spindle 67. The master cam 102 is driven by a link chain 115 from a sprocket 116 which is formed integral with or fixedly mounted on the sleeve 67. A sprocket 117 is mounted on the outer end of the master camshaft 100 so that when the sleeve 67 is rotated to transmit a rotary motion to the work piece being ground, a corresponding rotary motion is transmitted by the sprocket 116, the link chain 115, the sprocket 117, to rotate the master camshaft 100 and the master cam 102 so as to transmit a rocking motion to the rock bar 55 through the mechanism above described.

The operation of this apparatus is readily apparent from the foregoing disclosure. Assuming the adjustments of the various parts of the mechanism have been previously made, the work piece, such as a piston 69 (Fig. 2), is placed in position on the head stock supporting member 68 and the footstock center 71. The grinding wheel is then started rotating and a rotary motion is imparted to the work piece 69 by means of the headstock motor 18 which is connected in the manner above described to rotate the piston 69 at a uniform rate and at the same time to rotate the master cam 85 and transmit a rocking motion to the rock bar 55 to grind a non-circular shape on the piston 69. If for any reason it is desired to slightly change the long and short axis of the oval or ellipse produced on the piston, then the bracket 90 may be adjusted vertically and the fulcrum stud 89 may be adjusted in a like manner to vary the oscillating movement transmitted to the rock bar 55 by the master cam 85.

It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the accompanying drawings are to be interpreted as illustrative and not in a limiting sense.

I claim:

1. In a grinding machine for grinding non-circular work pieces, a rotatable grinding wheel, a pivotally mounted rock bar, a rotatable work support thereon including a rotatable spindle and a pair of opposed aligned work supporting centers, a pair of opposed aligned trunnions to support said rock bar, a rotatable master cam and a follower which are arranged to rock said bar to cause said work centers to approach and recede from said grinding wheel, and driving connections synchronously to rotate said spindle and master cam, said connections being arranged so that the master cam may be rotated at a different speed from the work spindle whereby a single lobed master cam may be utilized to produce a multiple lobed work piece.
2. In a grinding machine for grinding non-circular work pieces, a pivotally mounted rock bar, a rotatable work support thereon including a rotatable spindle and a pair of opposed aligned work supporting centers, a pair of opposed aligned trunnions to support said rock bar, a rotatable driving sleeve on one of said trunnions, a rotatable master cam and a follower, driving connections between said sleeve and said spindle to rotate said spindle, and driving connections between said sleeve and said master cam to rotate the master cam synchronously with said spindle.
3. In a grinding machine for grinding non-circular work pieces, a pivotally mounted rock bar, a rotatable work support thereon including a rotatable spindle and a pair of opposed aligned work supporting centers, a pair of opposed aligned trunnions to support said rock bar, a rotatable driving sleeve on one of said trunnions, a rotatable master cam and a follower, and driving connections between said sleeve and said spindle and between said sleeve and master cam synchronously to rotate said spindle and master cam, said driving connections being arranged so that the spindle may be rotated at a different speed from the master cam so that a single lobe master cam will grind a multiple lobe work piece.
4. In a grinding machine for grinding non-circular work pieces, a pivotally mounted rock bar, a rotatable work support thereon including a rotatable spindle and a pair of opposed aligned work supporting centers, a pair of opposed aligned trunnions to support said rock bar, a rotatable driving sleeve on one of said trunnions, driving connections between said sleeve and said spindle to rotate said spindle and work piece, a master cam on said sleeve, a pivotally mounted lever, a follower roller on one end of said lever, a link connecting the other end of said lever with the spindle, and an adjustable pivot stud for said lever which is located between said follower roller and said link whereby the lever arms may be adjusted to vary the extent of rocking movement of the work to vary the contour produced thereon.
5. In a grinding machine for grinding non-circular work pieces, a pivotally mounted rock

bar, a rotatable work support thereon including a rotatable spindle and a pair of opposed aligned work supporting centers, a pair of opposed aligned trunnion shafts to support said rock bar, a rotatable driving sleeve on one of said trunnions, gearing connections between said sleeve and said spindle to rotate the spindle and work piece, a master cam on said sleeve, a pivotally mounted lever, a follower roller on the lower end of said lever, a link connecting the upper end of said lever with the spindle, a pivot stud for said lever located between said follower roller and said link, an elongated slot in said lever to facilitate adjustment of said stud relative to said lever, a bracket supporting said stud, and means to adjust the position of said bracket so as to vary the position of said stud and thereby vary the distance between said follower and said stud and said stud and the link so as to vary the extent of rocking movement of the work to vary the contour produced thereon.

6. A grinding attachment for grinding non-circular work pieces adapted for use on a cylindrical grinding machine having a rotatable headstock spindle, an attachment frame arranged to be clamped on said machine, a rock bar pivotally supported on said frame, a rotatable work support on said bar including a rotatable spindle and a pair of opposed aligned centers, a pair of opposed trunnion shafts on said bar pivotally to support the rock bar on said frame, a rotatable driving sleeve on one of said trunnions, gearing connecting said sleeve to rotate said spindle whereby the work spindle rotates at half the speed of the sleeve, a master cam on said sleeve having a single lobe thereon, a master cam follower, and adjustable lever connections between said follower roller and said spindle whereby the rock bar is oscillated when the cam is rotated, said driving gearing and single lobe cam being arranged to oscillate the rock bar twice for each rotation of said spindle whereby a single lobe cam will produce diametrically opposed lobes on the work piece.

7. In a grinding machine for grinding non-circular work pieces, a pivotally mounted rock bar, a rotatable work support thereon including a rotatable spindle and a pair of opposed aligned work supporting centers, a pair of opposed

aligned trunnions to support said rock bar, a rotatable driving sleeve on one of said trunnions, driving connections between said sleeve and said spindle to rotate a work piece mounted thereon, a rotatable master cam which is arranged to be rotated by said sleeve, and adjustable lever connections including a follower roller whereby the motion of said cam is transmitted to oscillate said rock bar so as to produce a predetermined contour on a work piece.

8. In a grinding machine for grinding non-circular work pieces, a pivotally mounted rock bar, a rotatable work support thereon including a rotatable spindle and a pair of opposed aligned centers, a pair of opposed aligned trunnions to support said rock bar, a rotatable driving sleeve concentric with one of said trunnions, driving connections between said sleeve and said spindle to rotate a work piece supported thereon, a rotatable master cam, driving connections between said sleeve and said master cam to rotate the latter, a rotatable follower roller, and adjustable lever connections between said follower roller and said spindle whereby motion of said cam is transmitted to oscillate the spindle and rock bar during rotation of said spindle to produce a predetermined contour on said work piece.

9. In a grinding machine for grinding non-circular work pieces, a pivotally mounted rock bar, a rotatable work support thereon including a rotatable spindle and a pair of opposed aligned centers, a pair of opposed aligned trunnions to support said rock bar, a rotatable driving sleeve concentric with one of said trunnions, driving connections between said sleeve and said spindle to rotate a work piece supported thereon, a rotatable master cam, driving connections between said sleeve and said master cam to rotate the latter, a rotatable follower roller, adjustable lever connections between said follower roller and said spindle whereby motion of said cam is transmitted to oscillate the spindle and rock bar during rotation of said spindle to produce a predetermined contour on said work piece, and means to adjust said lever connections whereby the extent of oscillation of said spindle and rock bar may be varied to vary the shape produced on the periphery of the work piece.

CLARENCE J. GREEN.
